SAFETY RAZOR HAVING ADJUSTABLE GUARDS

Jean-Baptiste Raoul Savary, Paris, France;
vested in the Alien Property CustodianApplication February 11, 1939, Serial No. 255,816
In France February 25, 1938

4 Claims. (Cl. 30—71)

The present invention has for object improvements in safety razors having movable guards.

The problem, which is solved by the applicant, consists in ensuring, in all the very different positions of holding the razor, and according to the pressure exerted by the user, a modification of the amount by which the cutting edge of the blade projects relatively to the plane tangent to the cap and to the guard, while the distance separating the guard from the cutting edge of the blade either remains unaltered or is temporarily decreased when the pressure exerted by the user increases.

According to the invention, the safety razor having adjustable guards and in which the blade is held rigidly in position, is characterised by the fact that each guard is resiliently mounted or is so devised as to constitute a yieldingly shiftable element which can move towards the cutting edge of the blade, in proportion as the pressure exerted by the user increases, whilst ensuring an increase of the amount by which the blade projects relatively to the plane tangent to the cap and to the corresponding guard.

In the accompanying drawing, given by way of example only:

Fig. 1 is a general elevation of a razor devised according to the invention.

Fig. 2 is a section made according to line II—II of the preceding figure.

Fig. 3 is a partial elevation of another form of construction and showing the resilient mounting of an automatically adjustable guard.

Fig. 4 is a section made according to line IV—IV of the preceding figure.

Fig. 5 is a general elevation of a modification of the razor illustrated in Fig. 1.

Fig. 6 is a section made according to line VI—VI of the preceding figure.

In the example of Figs. 1 and 2, each guard 8 which has the form of a cam, is freely journalled on spindles 90. According to the invention, a spring 91 is partially wound on the spindle 90 and its ends are connected, one to the corresponding cam and the other to the lateral extension 55 of the seating member 2. A spring such as 91 is mounted at both ends of each guard. In a modification, a single spring is used which extends along the seating member for connecting one guard to the other. The various springs are suitably devised so as to allow a slight displacement of the cams or guards 8 when the latter are applied on the skin with a certain pressure. Thus, an automatic adjustment of the position of the plane tangent to the cap and to

the corresponding guard is obtained and, consequently, an automatic adjustment of the inclination of the cutting edge of the blade and of the amount by which said cutting edge projects relatively to said plane.

Figs. 3 and 4 illustrate another form of construction in which the cam or guard 8 is mounted on a spindle 90 by means of a rubber ring 94 or the like, said guard being angularly held between extensions 55 of the seating member 2. This ring can be compressed in position or obtained by spirally winding a rubber band rendered rigid through any suitable means (sticking, vulcanization) with the spindle 90 and the guard 8. Preferably, said ring is connected to the spindle 90 and to a socket 95 which is engaged in a corresponding perforation formed in cam 8, said socket 95 being then angularly connected to the cam.

The resilient mounting thus obtained operates substantially in the same manner as that indicated with reference to Figs. 1 and 2.

In the embodiment illustrated in Figs. 5 and 6, use is made of a mounting similar to that of Fig. 1. The ends of the springs 91 tend to urge the guards 8, 8 outward by pressing against corresponding abutments of the seating member 55 and of cam 8. Moreover, each guard 8 comprises a curved part 8^a.

What I claim as my invention and desire to secure by Letters Patent is:

1. In a safety razor, in which the blade is held stationary between a cap and a corresponding seating member, movable guards having mountings spaced below the seating member, resilient means for constantly retaining the guards resiliently projecting out beyond the cutting edges of the blade and constantly tending to prevent the displacement of the guards inwardly from said projecting positions, so that each guard moves inwardly towards and beneath the cutting edge of the blade in proportion as the pressure exerted directly against said guards by the user increases during use, while ensuring an increase of the amount by which the blade projects relatively to the plane tangent to the cap and to the corresponding guard, and means preventing the projection of each movable guard outward beyond a predetermined position beyond the blade.

2. In a safety razor, in which the blade is held stationary between a cap and a corresponding seating member, movable guards resiliently mounted so as to be constantly retained resiliently projecting out beyond the cutting edges

of the blade and so that each guard moves inwardly towards and beneath the cutting edge of the blade in proportion as the pressure exerted directly against said guards by the user increases during use, while ensuring an increase of the amount by which the blade projects relatively to the plane tangent to the cap and to the corresponding guard, each guard having a mounting spaced below the seating member, and means preventing the projection of each movable guard outward beyond a predetermined position beyond the blade.

3. In a safety razor, in which the blade is held stationary between a cap and a corresponding seating member, freely movable pivoted guards, spindles spaced beneath the seating member constituting pivots for the guards and springs wound on said spindles having ends which respectively press on said guards and the seating member of the blade so as to maintain the guards resiliently projecting out beyond the cutting edges of the blades and tending to prevent the displacement of said guards inwardly from their projecting positions so that each guard moves inwardly towards and beneath the cutting edge of the blade in proportion as the pressure exerted directly against said guards by the user increases during use, while ensuring an increase of the amount by which the blade pro-

jects relatively to the plane tangent to the cap and to the corresponding guard, and means preventing the projection of each movable guard outward beyond a predetermined position beyond the blade.

4. In a safety razor in which the blade is held stationary between a cap and a corresponding seating member movable guards having pivotal mountings including spindles spaced below the seating member, resilient means including a rubber member mounted directly upon each spindle and urging the guard associated therewith resiliently outward away from the blade to project beyond the adjacent cutting edge thereof and constantly tending to prevent displacement of the guard inwardly from its projecting position, so that each guard moves inwardly towards and beneath said adjacent cutting edge of said blade in proportion as the pressure exerted directly against said guard by the user increases during use, while ensuring an increase of the amount by which the blade projects relatively to the plane tangent to the cap and to the corresponding guard, and said resilient means also preventing the projection of each of the guards outward substantially beyond a pre-determined position beyond the blade.

JEAN-BAPTISTE RAOUL SAVARY.
